[57] ABSTRACT

An upright open top support and guide structure is provided defining an upstanding elevator passage and a horizontal support platform is mounted in a lower portion of the passage for support of an upwardly

opening basket therefrom. Manually operable lift structure is also guidingly mounted on the guide structure for vertical shifting therealong and is operable to lift a basket supported on the platform. The guide structure includes vertically spaced sets of automatically retractable abutment-type support members or dogs and each set of support members or dogs is laterally outwardly retractable in response to the movement of a basket upwardly therewith and thereafter automatically laterally inwardly extendable to a position beneath the basket to support the latter in elevated position. The lift structure includes vertically spaced sets of laterally inwardly displaceable abutment portions for automatically engaging and lifting baskets in the guide structure and in the event the upper basket has been upwardly manually withdrawn from the open top of the guide structure the lower abutment portions include lower portions which are automatically inwardly displaced for engaging and lifting a lower basket within the guide structure. If the upper basket has not been removed, the abutment portions moving upwardly therewith engage stationary cams to positively outwardly displace the abutment portions from engagement with the upper basket. In this manner, the lift structure may be repeatedly actuated to elevate baskets added to the lower end of the guide structure upwardly through the latter to an upper position therein for manual withdrawal from the upper end of the guide structure.

FIG. 5

RACKS FOR BOTTLES, CANS AND GLASSES

This invention comprises an improvement over the invention disclosed in my prior U.S. Pat. No. 3,759,593.

BACKGROUND OF THE INVENTION

There are many instances when open top trays or racks for bottles, cans and glasses are contained within cabinets to whose interior access may be had through openings formed in the tops of the cabinets. In this manner, the articles supported from the racks or trays may be readily withdrawn from the open tops of the cabinets until the supply of articles in the uppermost rack or tray is exhausted. Then, it is conventional to remove the uppermost rack or tray from the cabinet and to thereafter utilize the supply of articles disposed in the rack or tray therebeneath. However, a convenient means must be provided to elevate the next rack to an uppermost position within the cabinet in order that the articles therein may be most conveniently placed for ready access thereto through the open top of the cabinet.

Racks and open top trays of the aforementioned type are many times utilized to support large numbers of articles of considerable weight and accordingly a full rack or tray of articles constitutes a load which is difficult to elevate. Accordingly, elevating structure is often provided in these types of cabinets for elevating vertically spaced trays or racks of articles disposed therein. Examples of previously patented structures of this type may be found in U.S. Pat. Nos. 2,322,439; 2,614,020; 3,531,169 and 3,737,209.

BRIEF DESCRIPTION OF THE INVENTION

The rack supporting structure of the instant invention comprises a guide structure defining an upstanding elevator passage having a support platform mounted therein for vertical movement therethrough. A lift structure is provided for lifting the platform and the guide structure includes variously actuatable support members or dogs for engaging and supporting vertically spaced racks in adjusted vertical positions within the guide structure. Further, the lift structure includes automatically actuatable abutment portions shiftable between operative and inoperative positions for engaging and lifting racks within the guide structure spaced above the support platform as the support platform is moved to a raised position. In this manner, a plurality of vertically stacked racks may be elevated to predetermined positions and supported in those positions after which the support platform for the lowermost rack may be lowered to the bottom of the guide structure for the reception of a lower rack thereon to be subsequently elevated through the guide structure.

The main object of this invention is to provide a support and guide structure for a plurality of vertically spaced racks or trays for supporting various articles and lift structure operatively associated with the guide structure for elevating the racks within the guide structure.

Another object of this invention, in accordance with the immediately preceding object, is to provide elevating structure for engaging and elevating racks disposed within the guide structure that will automatically sense the removal of the uppermost rack within the guide

structure and function to elevate the next lower rack to the uppermost position within the guide structure.

Yet another important object of this invention is to provide manually operable actuator means for the lift structure which may be utilized to lift a plurality of reasonable heavily laden racks within the guide structure with a minimum of effort.

A final object of this invention to be specifically enumerated herein is to provide an apparatus in accordance with the preceding objects and which will conform to conventional forms of manufacture, be of simple construction and easy to use so as to provide a device that will be economically feasible, long lasting and relatively trouble free in operation.

Other objects and advantages of the present invention will become apparent from the following description of the preferred embodiment when taken in conjunction with the accompanying drawings.

BRIEF DESCRIPTION OF THE DRAWINGS

FIG. 1 is a side elevational view of the rack support and guide structure of the instant invention with an alternate position of the manually operable actuator for the support platform thereof illustrated in phantom lines;

FIG. 2 is a fragmentary horizontal sectional view taken substantially upon the plane indicated by the section line 2-2 of FIG. 1;

FIG. 3 is an enlarged fragmentary vertical sectional view taken substantially upon the plane indicated by the line 3-3 of FIG. 1;

FIG. 4 is a fragmentary horizontal sectional view taken substantially upon the plane indicated by the section line 4-4 of FIG. 3;

FIG. 5 is a fragmentary perspective view illustrating one of the stationary cam members of the support and guide structure; and

FIG. 6 is a fragmentary exploded perspective view of various of the components of the lift structure of the instant invention.

DETAILED DESCRIPTION OF THE INVENTION

Referring now more specifically to the drawings the numeral 10 generally designates the support and guide structure of the instant invention. The structure 10 includes four upright corner members 12 interconnected at their lower and upper ends along the opposite sides of the structure 10 by means of lower and upper brace members 14 and 16 extending therebetween on opposite sides of the guide structure 10. In addition, corresponding opposite ends of the members 14 and 16 are interconnected by means of transverse members 20 and 22 extending therebetween.

The central portions of each pair of vertically spaced members 14 and 16 are rigidly interconnected by means of vertical guide angle members 24 and 26 slightly spaced apart along the members 14 and 16. An elevator bar 28 is embracingly engaged by each pair of vertical guide angle members 24 and 26 and each elevator bar 28 includes a lower end fastener 30 secured therethrough and slidably received in the slot 34 defined between the corresponding angle members 24 and 26.

A pair of rearwardly and upwardly inclined tracks 36 are secured between the lower ends of the forward corner members 12 and the corresponding angle members 24 at points spaced slightly above the lower ends of the

latter. An L-shaped elevator member referred to in general by the reference numeral 40 is provided and includes a pair of opposite side long vertical legs 44 terminating downwardly in horizontally inwardly directed short horizontal legs 46. The free ends of the horizontal legs 46 are pivotally anchored to the corresponding fasteners 30 and the fasteners 30 are also secured through slide plates 48 disposed in sliding contact with the outer surfaces of the corresponding angle members 24 and 26. Also, the ends of the short horizontal legs 46 adjacent the lower ends of the long vertical legs 44 of the elevator members 40 are provided with rollers 50 rollingly engaged with the corresponding tracks 36. In this manner, the elevator member 40 may be swung from the solid line inoperative position thereof illustrated in phantom lines in FIG. 1 with the elevator bars 28 in elevated positions.

The lower end portions of each pair of end corner members 12 have additional transverse brace members 52 secured therebetween spaced above the lower ends of the members 12 and the transverse members 52 include parallel longitudinal support members 54 spaced transversely of the structure 10 secured therebetween. The longitudinal members 54 are operative to support a lower upwardly opening tray or rack 56 therefrom.

Each pair of vertically spaced members 14 and 16 have a pair of front to rear spaced upstanding support members 56 and 58 secured therebetween with each support member 56 and 58 spaced generally equally between a corner member 12 and the adjacent angle member 24 or 26.

A pair of vertically spaced cam frames 60 and 62 are supported from each support member 56 and 58 and a pair of vertically spaced support brackets 64 and 66 are also supported from each support member 56 and 58 in general horizontal alignment with the corresponding cam frames 60 and 62. Each support bracket 64 and 66 pivotally mounts a ratchet dog 68 therefrom with each dog 68 being swingable between a substantially upstanding position limited by a stop flange 70 on the corresponding support bracket and an upwardly and inwardly inclined position limited by the main body portion of the corresponding support bracket.

Also supported from each elevator bar 28 by means of spacer blocks 74 slidably received in the corresponding slot 34 and by means of fasteners 76 secured through the corresponding spacer blocks 74 are a pair of split support blocks 78 through which the fasteners 76 are secured. Each split support block 78 includes a pair of block sections 80 having opposing horizontal semi-cylindrical recesses 82 formed therein and each pair of opposing semicylindrical recesses defines a cylindrical bore in which the bight portion 84 of a U-shaped frame 86 is oscillatably supported. Each frame 86 includes a pair of generally parallel legs 88 which terminate at their free ends in outwardly directed arms 90 having U-shaped feeler guides 92 and abutment pins 94 supported therefrom.

The upper and lower U-shaped frames 86 on each side of the structure 10 are substantially identical, except that the frame guides 92 of the upper U-shaped frames 86 are slightly shorter than the frame guides 92 of the lower frames 86.

Each of the vertical guide angle members 24 and 26 includes a pair of vertically spaced horizontally outwardly directed abutment pins 98 with which the legs of the corresponding frames 86 are engagable.

In addition, each split block 78 has a horizontally inwardly opening U-shaped frame 100 secured thereto by the fasteners 76 and including a pair of horizontally inwardly directed legs 102 including inner end inwardly directed abutment flanges 104 with which the legs 88 of the corresponding frames 86 are abuttingly engagable to limit inwardly swinging movement of the free ends of the legs 88 of each frame 86 and the U-shaped feeler guides 92 supported therefrom.

In operation, an upwardly opening basket or rack 56 may be placed on the longitudinal members 54 through the front of the structure 10 whenever the longitudinal members 54 do not have a rack supported therefrom. Then, if it is desired to raise the rack 56, the elevator member 40 has the upper ends of the long vertical legs 44 thereof, which upper ends may be rigidly interconnected by means of a horizontal connecting member (not shown), swung downwardly and outwardly to the phantom line position of the elevator member 40 illustrated in FIG. 1 of the drawings. By thus angularly displacing the elevator member 40, the elevator bars 28 are elevated between the vertical guide angle members 24 and 26 moving the split blocks 78 upwardly therewith. As the lower frame 86 is elevated the legs 88 thereof ride upwardly along the corresponding pins 98 and allow the frame 86 and the feeler guides 92 supported therefrom to angle inwardly over the basket 56. Inward tilting of the lower frames 86 is continued until the feeler guides 92 thereof abut the upper rim of the basket or rack 56 and the pins 94 engage the under portion of the upper rim of the rack 56. Thereafter, further upward movement of the elevator bars 28 elevates the rack 56. Upward movement of the rack 56 through the structure 10 causes the upper portion of the rack 56 to engage the ratchet dogs 68 so as to swing the latter outwardly toward their retracted positions until the lower end of the rack 56 passes the upper portions of the lower ratchet dogs 68 whereupon the latter are free to fall inwardly beneath the rack 56 for support of the latter therefrom as soon as the elevator member 40 is swung from the phantom line position thereof illustrated in FIG. 1 to the solid line position in order to lower the elevator bars 28.

With the first inserted rack 56 thus supported in elevated position above the longitudinal members 54 by the lower set of ratchet dogs 68, a second rack 56 may be placed on the longitudinal members 54. Then, if the elevator member 40 is again actuated to raise the elevator bars 28 the upper ends of the lower feeler guides 92 slide along the upper rack 56 until the free ends of the arms 90 engage the lower cam frames at which point the lower feeler guides 92 are swung outward to inoperative positions. However, upper displacement of the elevator bars 28 also raises the upper frames 86 and the feeler guides 92 thereof are displaced inwardly over the upper rack 56 as the legs 88 of the upper frame 86 slide upwardly along and over the corresponding pins 98. Thus, the feeler guides 92 of the upper frame 86 incline inwardly over the upper basket 56 and the pins 94 of the upper frame 86 engage the upper rim of the upper basket or rack 56 in order to elevate the latter into position above the upper set of ratchet dogs 68. Of course, after the rack 56 supported from the upper ratchet dogs 68 is removed from the top of the structure 10 the lower rack 56 may be elevated to the lower set of ratchet dogs 68 and thereafter to the upper set of ratchet dogs 68 as hereinbefore set forth.

Inasmuch as the present invention is subject to many variations, modifications and changes in detail, it is intended that all matter contained in the foregoing description or shown in the accompanying drawing shall be interpreted as illustrative and not in a limiting sense.

What is claimed is:

1. In combination, an upright open top support structure defining an elevator passage extending upwardly therein, said support structure including support means in a lower portion of said passage for supporting a rack therefrom, said support structure further including ratchet structure spaced vertically therealong for supporting a plurality of racks in vertically spaced relation within said passage against downward displacement therein and for substantially free upward displacement relative to said ratchet structure, elevator means guidingly supported from said rack structure for elevational shifting therealong, said elevator means including rack engaging means shiftable between operative rack engaging position and inoperative rack by-passing position, said rack engaging means and support structure including means for sensing a lower rack in said support structure below an upper rack and shifting said rack engaging means to the inoperative position while moving upwardly past said lower rack and to the operative position thereof when moving upwardly past the upper rack for supportively engaging the latter and elevating the same to the next higher ratchet structure for support therefrom in response to further upward movement of said elevator means.

2. The combination of claim 1 wherein said elevator means includes vertically spaced sets of said rack engaging means.

3. The combination of claim 1 including manually operable actuator means for elevating said elevator means.

4. The combination of claim 3 wherein said manually operable actuator means includes an upright L-shaped lever structure including an upstanding long leg portion extending downwardly along one marginal side of said support structure and terminating in an inwardly directed short leg portion pivotally attached at its free end portion to said elevator means, said lever structure, adjacent the juncture of said short and long leg portions including follower means pivotally supported therefrom, and inwardly and upwardly inclined track means carried by said support structure and extending inwardly from a lower marginal portion of said one marginal side of said support structure with which said follower means is guidingly engaged for movement therewith.

5. The combination of claim 4 wherein said follower means comprises wheel means journaled from said lever structure and rollingly engaged with said track

means.

6. The combination of claim 1 wherein said ratchet structure includes vertically spaced sets of horizontally spaced ratchet dogs pivotally supported from said support structure for inward and outward swinging relative to said passage between operative and inoperative limit positions, respectively, said ratchet dogs eccentrically weighted for automatic inward swinging, by gravity, to the operative positions thereof and including portions 10 displaced inwardly of said passage when said dogs are in the operative positions and engageable by a rack being elevated therewith in said passage for causing said ratchet dogs outward toward their inoperative positions.

7. The combination of claim 1 wherein said rack engaging means include upstanding structures pivotally supported at their lower ends from said elevator means for inward swinging movement of the upper end portions of said upstanding structures into said passage 20 toward operative positions thereof and outward swinging of said upper end portions from said operative positions toward inoperative positions thereof, the upper end portions of said upstanding structures including supportive portions thereof operative, when said upstanding structures are in said operative positions and said elevator means is being elevated, to supportively engage and elevate a rack disposed in said passage.

8. The combination of claim 7 wherein said support structure includes abutment portions thereof engageable by said upstanding structures to retain the latter in the inoperative positions thereof when said elevator means is disposed at a predetermined elevation and to allow gradual swinging of said upstanding structures toward the operative positions thereof in response to elevation of said elevator means above said predetermined elevation and to swing said upstanding structures from said operative positions thereof to the inoperative positions in response to lowering said elevator means toward said predetermined elevation.

9. The combination of claim 8 wherein said support structure includes means operative to engage and shift said upstanding structures from positions with the upper portions thereof swung partially inwardly from said inoperative positions thereof toward said operative 45 positions in response to movement of said elevator means, through predetermined zones, in either direction, of elevation including upper and lower limits.

10. The combination of claim 9 wherein the upper end portions of said upstanding structures include portions thereof for engagement with an elevated rack supported in said support structure to limit inward swinging of said upper end portions of said upper portions to said partially inwardly swung positions.
